(57) **CLAIM**

The ornamental design for a can, as shown and described.

DESCRIPTION

FIG. 1 is a top perspective view of a can showing our new design;

FIG. 2 is a side view thereof;

FIG. 3 is a top view thereof; and,

FIG. 4 is a bottom view thereof.

The broken lines outlining the pull tab in FIGS. 1 and 3 are for illustrative purposes only and form no part of the claimed design.
